UNITED STATES PATENT OFFICE.

CHARLES J. WHITE, OF NEW BRITAIN, CONNECTICUT, ASSIGNOR TO THE C. J. WHITE MANUFACTURING COMPANY, OF NEW BRITAIN, CONNECTICUT, A CORPORATION OF CONNECTICUT.

BUTTON-TAB END FOR HOSE-SUPPORTERS.

1,210,574.

Specification of Letters Patent.

Patented Jan. 2, 1917.

Application filed February 28, 1916. Serial No. 80,851.

To all whom it may concern:

Be it known that I, CHARLES J. WHITE, a citizen of the United States of America, residing at New Britain, Connecticut, have invented a new and useful Button-Tab End for Hose-Supporters, of which the following is a specification.

My invention relates to a new and improved button tab end for hose supporters of the button and loop type.

The object of my invention is to provide an improved construction looking to economy, durability and finish, and which shall likewise avoid exposing any metal or component parts at the rear to come in contact with the body of the wearer. These and other advantages will be apparent to a mechanic skilled in the art from an examination of the accompanying drawings and a reading of the following specification, wherein I have shown and described certain preferred embodiments of my invention only, appreciating that various changes may be made without departing from the spirit and scope thereof.

In the drawings: Figure 1 is a front elevation of a tab end embodying my invention and illustrated on a relatively enlarged scale. Fig. 2 is a section on the line 2—2, of Fig. 1. Fig. 3 is a section on the line 3—3, of Fig. 1. Fig. 4 is a view similar to Fig. 1 showing a modification. Fig. 5 is a section on the line 5—5, of Fig. 4. Fig. 6 is a detail. Fig. 7 is a development view showing the back of the tab illustrated in Fig. 4 before it is in final form.

1 represents a button head which, in the preferred form, is oval and is secured by means of an oval shank 2 to a base 3. The button in its preferred form is undercut at its opposite sides only, although this is not essential in all forms. In my present invention, however, this form of button has especial advantages. In the tab end, the major diameter of the shank 2 preferably runs longitudinally of the tab end. The tab end comprises not only the button and its base, but also a fabric support which is flexible. The button may be made of any suitable material or compound, but is preferably molded from rubber, and the base 3, if desired, may be molded integrally therewith, this integral construction being preferred, and possessing distinct advantages.

4—5 are split plies of fabric, which extend

upwardly from the base 3, and which likewise substantially cover the front and rear of the base, one of said plies being punctured or slotted appropriately so that the head 1 and shank 2 may be passed therethrough. An appropriate slit for the button shown is indicated at 6, Fig. 6.

In the preferred construction the two plies 4—5 are united at one end of the base and in the particular construction shown in the drawings, said plies are connected at 7 so as to cover the lower edge of the base 3. Between the plies and the base is a suitable cementing agent which preferably should be rubber, whereby when the parts are assembled, as shown in Figs. 1, 2 and 3, the tab end may be passed through suitably heated rolls under pressure so as to vulcanize the rubber cementing agent and thus permanently unite the structure, causing the said plies respectively to adhere to each other and preferably to the front and rear face of the base 3. The width of the fabric covering for the base may be slightly in excess of the width of the base so as to cover the edges thereof. In Figs. 1 to 3 I have indicated the strip of fabric as of substantially the same width throughout. In the modification shown in Figs. 4, 5 and 7 the strip is indicated as of unequal widths, that is to say, the part 4^a of the strip is of greater width than the part 5^a thereof. In this case, the edges of the part 4^a may be folded in as indicated at 8—8, which edges may be cemented. The folded-in edges may extend the entire length of the tab end so as to cover the edges of the base 3^a. The part 5^a of the fabric may be of suitable width and suitably shaped to fit between the folded edges of the part 4^a and at the same time cover the back of the base 3^a. This modification is merely suggestive of one of the many modifications that may be resorted to.

By making the button shank 2 of oval form and arranging it longitudinally of the tab end the slit 6 in the fabric runs in such a direction that the said fabric is not materially weakened. I have found that by this construction there is no necessity for the application of metal fastening devices or clamps for securing the button to the fabric support. It also makes stitching unnecessary, thereby effecting substantial economies. I have found that such tab ends may be very rapidly produced and will possess great

durability and may be worn with the greatest comfort. They likewise present an attractive appearance.

As indicated at the outset, I have illustrated only certain preferred forms of the invention appreciating that various changes may be made therein without departing from the spirit and scope thereof. I have found that a woven, knitted or felted textile fabric is particularly useful for the support as this not only affords a good base for the adhesive but it is also light, flexible and inexpensive. Leather or imitation leather may also be employed. The connection between the plies at the point 7 is preferably made by simply folding a strip of fabric on itself as such a method will produce the most effective connection from the standpoint of durability and appearance. The cementing agent may be in the form of a separate sheet inserted between the plies or it may be a coating on the surface of the fabric.

What I claim is:

1. In a button tab end, a button comprising a head and a base, a strip of flexible material folded to form two overlapping plies extending around the lower edge of said button base, said strip being perforated to permit the button head to pass therethrough, with means for causing the overlapped portion of said plies above said base to permanently adhere to each other, said adhesive means adding stiffness to said folded strip. 25

30 2. In a button tab end, a button comprising a head and a base, a strip of fabric comprising two overlapping plies enveloping said base, one ply of said strip being perforated to permit the button head to pass therethrough, with means for causing the overlapped portion of said plies above said base to permanently adhere to each other, said adhesive means adding stiffness to said strip. 35

CHARLES J. WHITE.
